SYNCHRONIZING SIGNAL GENERATOR

Kurt Schlesinger, West Lafayette, Ind., assignor to Radio Corporation of America, a corporation of Delaware

Application July 30, 1942, Serial No. 452,921

8 Claims. (Cl. 178—69.5)

This invention is directed to television systems, and particularly to a method and means for producing synchronizing signals (hereinafter termed "sync" signals because of usage in the art).

Further, the invention is directed to systems wherein the produced sync signals shall be in accordance with standards proposed by the Federal Communications Commission and reported in its Docket 5806, dated May 3, 1941.

In the prior art, sync signal generators have been developed and used successfully. Such apparatus has been proposed in various forms, and one form which has been used, to some extent, is that disclosed in brief form in "Principles of Television Engineering" by D. G. Fink, published by McGraw-Hill Book Company, Inc., New York, 1940, and particular reference is made to that portion of the publication referred to which commences on page 402, under the title "Synchronizing Signal Generator," and which continues through page 414.

In the prior art arrangements for instance, the sync signal generator included, mainly, two units, of which one was generally designated as the timing unit and the other was designated as the shaping unit. The timing unit is usually interlocked with a power supply frequency and serves to control the second unit which, as before stated, is known as the wave shaping unit. These various units are described in some detail in the publication hereinabove referred to, and, when in operation, serve to provide a synchronizing signal wave form of the general character herein-after disclosed by Fig. 1 of the drawings which will be described in what is to follow.

The wave form for controlling television image reproduction generally comprises horizontal synchronizing pulses which, after a predetermined time, are followed by certain equalizing pulses. The equalizing pulses are six in number and occur at twice the line frequency, or, in other words, at twice the frequency of the horizontal synchronizing pulses. Following the six equalizing pulses there are produced vertical synchronizing pulses over a period of time corresponding to the time required to produce three lines of picture transmission. The vertical synchronizing pulses are each slotted, so there result, in effect, six separate slotted pulses. These vertical impulses are then followed by six additional equalizing pulses occurring at double line frequency which, together, occupy in time a period equivalent to that required to produce three separate lines of picture transmission.

Following the second group of equalizing pulses are a certain predetermined number of horizontal synchronizing pulses, after which the picture or video intelligence is again re-transmitted and followed after each line by a separate synchronizing pulse until the time for again initiating the first of the equalizing pulses above referred to again occurs, which, as is evident, will be at the time of completing each succeeding picture field transmission.

According to the proposed standards for transmission, vertical blanking in the picture is intended to take place during the period of transmission of all of the first group of equalizing pulses, the group of vertical synchronizing pulses, the second group of equalizing pulses, and a certain portion of the succeeding group of horizontal synchronizing pulses. The vertical blanking period may thus be assumed to include a period of time (according to proposed standards) corresponding to $0.075 V \pm 0.005 V$, where V represents the time from the start of one picture field to the start of the next succeeding picture field.

According to the present invention, it is proposed to develop, with apparatus of a substantially simplified nature, synchronizing signals of the general form hereinabove described and known in the art, and to this end, provision is made for accomplishing the results by purely electronic means of simplified nature.

It is an object of the present invention to provide a system for producing television synchronizing signal wave forms particularly adaptable for amplitude modulation of the video intelligence which conform completely to presently existing standards.

Another object of the invention is to provide for developing signals of the aforesaid character by means of purely electronic apparatus.

Still another object of the invention is to provide a system for developing synchronizing signals where all of the signals are derived from one and the same master oscillator which is preferably a non-sinusoidal pulse generator of pre-distorted wave form.

Another object is to provide for generating signals of the above character with apparatus which overcomes one or more known and existing disadvantages and defects of the prior art arrangements. For example, the relative phase shift of signal is made invariable with the present apparatus, and all groups of signals have the same leading edge in common.

A further object of the invention is to provide and develop a system wherein the number of

tubes required to generate the desired form of signal is substantially reduced.

Still a further object is that of developing a system for generating signals of the aforesaid character, wherein all switching operations are carried out substantially without inertia, and wherein the same output amplifiers are used to shape the various signals and thereby to reduce the number of tubes.

Still other objects and advantages are those of developing an efficiently operating synchronizing signal generator which occupies a relatively small space because of the reduced number of tubes and other component parts to provide a system for developing signals of the aforesaid character which is easily serviced and maintained in satisfactory stable operation, and a system which is relatively simple in its arrangement and construction.

Other and further objects and advantages naturally will become apparent to those skilled in the art from a reading of the following specification in connection with the accompanying drawings, wherein—

Fig. 1 is a diagrammatic representation of the general form of synchronizing signal now considered as standard;

Fig. 2 is a schematic representation of certain wave forms serving to illustrate the general principles of operation of the herein to be described device;

Fig. 3 is a schematic block diagram of the circuit instrumentalities herein to be disclosed;

Fig. 4 is a diagrammatic representation of certain wave forms occurring in the apparatus diagrammatically represented by Fig. 3;

Fig. 5 is a series of curves relating particularly to the operation of the single pulse relay schematically disclosed as a part of Fig. 3 and more particularly set forth by Fig. 6; and,

Fig. 6 is a schematic diagram of one form of the complete circuit instrumentalities diagrammatically represented in block form by Fig. 3.

Referring now to the drawings for a further understanding of the invention, the system in general is based upon an arrangement wherein the various groups of sync signals, namely, the line pulses, the equalizing pulses and the frame pulses (commonly referred to as L. E. F.), as well as the blanking signals, are derived from one and the same master oscillator by relatively simple clipping devices to which variable biases are applied. The master oscillator generates pulse energy of a predetermined non-sinusoidal wave form in which the duration is made equal to that desired for the equalizing pulses and the repetition rate is twice the line frequency. For each oscillatory cycle the energy is first negative and then positive with cessation of operation after the negative and positive pulses for approximately 76% of the cycle.

Such a system, as will herein be described in more detail, offers an important advantage in that the relative phase relation is invariable at all times, and all signal groups have the same leading edge in common, so that the phase relationship between all groups of signals is always fixed and correct.

According to some prior art systems, frequency demultiplication types of arrangements have been resorted to for the production of the framing signal, and though such systems are rather stable in operation and produce the desired de-multiplication factor, they cannot be relied upon entirely, because the phase relationship between

the input and the output signals is subject to variance to some extent. Therefore, the present invention does not attempt to use the output of a frequency de-multiplexer to produce the framing signal directly, because such a produced signal would be subject to shift in a somewhat erratic manner with reference to the line signals, but, by making provisions so that the output signal is taken as a sort of potential impulse, for instance, a highly precise timing signal may be obtained by using the impulse from the master oscillator to control the final signal production.

It will be apparent from the showing of Fig. 1 that the television synchronizing wave form, as it has now been approved by the Commission, comprises recurring line synchronizing impulses 1 which occur with their leading edges spaced with a time separation H (one picture line period). At the bottom of each picture field transmitted, a series of six equalizing pulses 3 are initiated. These equalizing impulses are each of the same amplitude as the line synchronizing impulses, so that in transmission they represent, as do the line synchronizing impulses, substantially 100% modulation of the carrier. However, the equalizing impulses are of less width and less duration than the line synchronizing impulses, and, according to the adopted standards, the area is permitted to vary between 0.45 and 0.5 of the area of each horizontal or line synchronizing impulse. After the series of six equalizing pulses are developed these are followed by the vertical synchronizing impulses 5, which are slotted as shown at 7.

The time period indicated between the beginning of one vertical synchronizing impulse and the beginning of the next succeeding vertical synchronizing impulse is 0.5 times the time between any two successive line synchronizing impulses.

40 The width of the slotted portion of the vertical synchronizing impulse is to be equal to approximately 0.07H, where H is the time from the start of one line synchronizing pulse to the start of the next line synchronizing pulse, so that it becomes evident that the width of each vertical synchronizing pulse is approximately 0.43H.

After the succession of six vertical synchronizing pulses 5 has been produced within the time period represented by three times the time expiring between the beginning of one line synchronizing impulse and the beginning of the next succeeding line synchronizing impulse, a second series of equalizing pulses 3', also six in number, is developed, and these equalizing pulses then are followed by the normal line synchronizing pulses 3.

60 The time period between the start of the first equalizing impulse of the first group and the commencement of the next succeeding transmission of video signals represented conventionally at 11, is made equal substantially to 0.075 V, where V represents the time from the start of one picture field to the start of the next picture field, and, according to the illustrated wave form, it will be seen that eight horizontal synchronizing pulses follow the second group of six equalizing pulses prior to the commencement of the transmission of video signals, represented at 11, for the top of the next picture field.

65 As shown, each horizontal synchronizing pulse, each equalizing pulse and each vertical pulse is maintained at substantially 25% greater carrier voltage than any video signal 11, as is customary in any system wherein "negative modulation" is provided, by which is meant that white of

maximum brilliance in the picture is represented by zero carrier, the black, as black in the picture, is represented by 75% modulation of the carrier, and all synchronizing and equalizing pulses represent substantially 100% modulation of the carrier, and consequently produce signals which can be described as being "blacker than the blackest black."

With the foregoing thoughts in mind, reference may be made to Fig. 2 of the drawings, and first to curve *a* thereof. By this curve, as in all others, the ordinates represent amplitude and the abscissae represent time. By referring to curve *a* of Fig. 2, it will be seen that this curve represents generally the wave form 15 of the master oscillator which develops output pulse energy at a frequency of 31,500 cycles per second (assuming a 525 line television picture as will be herein assumed for illustrative purposes). Thus, the elapsed time between any two peaks of the output energy is represented as $\frac{1}{31,500}$ second, and the width of the pulse in the negative direction (to form the slots in the vertical sync) is represented as 8% H, where again H, as in Fig. 1, represents the time elapsed between the starting of one line and the starting of the next succeeding line, while the width in the positive direction (to develop the equalizing pulses) is 4% H.

It can be seen from the showing of curve *a* of Fig. 2 that the master wave thus developed is a sequence of pulses occurring in the desired width and at the desired frequency and starting with a peak in the negative direction. Each wave trace, comprising the negative and the positive half, has a combined period of 12% of the repetition period of each line, with the duration of either the positive portion of the pulse amounting to 4% of the line frequency, which line frequency may be derived from the master frequency by a frequency reduction of the order of 1:2. The 4% width is intended to be the duration of the equalizing pulses to occur between the line synchronizing pulses and the vertical synchronizing pulses, as was hereinabove explained, in accordance with the standards of the RMA and those recommended by the Federal Communications Commission, all as above stated.

In curve *a* of Fig. 2, one clipping level, above the zero reference line O, in the positive direction has been indicated by the legend E, from which the equalizing pulses will be derived, and a second clipping level has been indicated as spaced from the zero reference line O by a distance represented by F from which the frame synchronizing signals are to be derived. There thus results from clipping the master wave at the level E, a series of pulses such as those shown, for instance, by curve *b* of Fig. 2, which appear as a series of pulses 17 each spaced in time, one from the other, by $\frac{1}{31,500}$ second, and for a resultant signal resulting from clipping, at the level F, a signal such as that shown schematically by curve *c* of Fig. 2 is found to be developed. This series of signals will be those resulting from clipping below the zero line of curve *a*, and consequently there is produced a series of indications represented by an amplitude 19 with depressions or recesses 21 which correspond in width (8% H) to the width of the slots 7 in the vertical sync pulses.

It can be seen that in the elapsed time between the commencement of each pulse 18, there elapses a time corresponding to the time between the start of each succeeding line of synchroniz-

ing impulses and the interruption periods designated by the recesses 21 provide signal interruptions existing for 8% of the line period, as shown by curve *a*, and which thus correspond to the periods of interruption in the vertical sync pulse interval 7, as shown by Fig. 1.

It can be seen further, from what has been above stated, that the leading edge of both the equalizing pulses 17 and the frame signals 19 are coincident in time. The line and the blanking signals are derived from the same master wave by frequency halving after the master wave is inverted, as shown by curve *d* of Fig. 2.

Let it now be assumed that the frequency halver responds to a positive peak and is given an exponential output wave shape by a capacity loading. The wave form may be considered to be as shown by curve *e* of Fig. 2. In this case, the blanking and super sync pulses may be derived from the output, again by two clipping procedures indicated by clipping at the levels S and B representing, respectively, the clipping levels for the high level super sync signals and low level blanking signals. The S level clipping 25 may easily be placed at such a voltage that the leading edge of the resultant sync pulse becomes coincident with the leading edge of the equalizers and frame signals, as is shown, for instance, by curve *f* of Fig. 2, and in this instance the super sync signals 25 are shown as being approximately 8% of the line period. From clipping at the lower level or B level, as indicated by curve *e* for the production of the blanking signals, it can be seen that a blanking signal, such as that shown 30 by curve *g* of Fig. 2, will result, and that this signal is broader than the super sync and furthermore that it precedes the super sync and controls it, as required by the standards. Such pulses are represented schematically by the 35 blanking signals conventionally shown at 27.

Reference may now be made to Fig. 3 of the drawings which is a schematic representation of the general arrangement of the various tube circuits, which, in co-operative relationship, produce the various clipping and wave shaping effects schematically represented in Fig. 2 above discussed. In connection with a consideration of the diagrammatic representation of Fig. 3, reference should also be had to Fig. 4, wherein various 40 wave shapes appearing in the different instrumentalities diagrammatically represented in Fig. 3, are indicated. By the various portions of Fig. 4, the letters indicate the wave shapes at the 45 points where the letter indications appear in 50 Fig. 3.

Referring now to Fig. 3, the master oscillator 31 is provided for developing pulse energy of a wave form shown, for instance, by the waves of Fig. 2a or Fig. 4a. These pulses are generated 55 as was indicated, to be repeated at a frequency of 31,500 cycles per second (assuming herein, as above stated, that the system disclosed is operating with a 525 line television picture, although it is perfectly evident that the same circuits are applicable to systems using a different number of picture lines and a different number of picture frames and fields than the assumed 30 and 60 respectively). It was above noted also that the wave should be inverted to produce some of the effects necessary.

It has accordingly been provided so that the master oscillator 31 is the source from which three separate signals are derived. To provide 60 this effect, the output from the master oscillator

is supplied (first) to a cathode follower or buffer stage 33; (second) to supply an inverted output wave such as that shown by Fig. 2d or Fig. 4b to the line oscillator 35 and a frequency divider 37, and (lastly) to control a super sync mixer 39 with a wave form such as shown in Fig. 2a. The cathode follower or buffer stage 33 feeds its output, in turn, to a series of frequency dividers 41, 42, 43 and 44 respectively, each of which is driven from the preceding oscillator, and the cathode follower or buffer stage 33 acts to prevent any possible load variations in the frequency divider stages from being introduced upon the master oscillator 31 by the controlled frequency reducing system.

The line oscillator 35 is adapted to generate output energy at a frequency which is half that of the master oscillator 31, and, accordingly, the output pulses therefrom occur at a rate of 15,750 cycles per second. Along with the line frequency oscillator 35, the inverted energy from the master oscillator 31 is applied also to a frequency divider unit 37 which operates to develop an output frequency which is $\frac{1}{3}$ that of the master oscillator, or 5,250 cycles, which is keyed for the duration of the frame pulses.

Finally, the master oscillator also feeds its noninverted output wave, such as that shown by Fig. 2a or Fig. 4a, to the super sync mixer 39, wherein wave formations corresponding to waves e, f and g of Fig. 2 are developed by suitable clipping actions.

As was above stated, the master oscillator generates its wave output, such as that shown by Fig. 2a or 4a, so that it starts with a negative peak. From the cathode follower or buffer stage 33, a series of positive pulses, at double line frequency, as shown by the pulses of wave form Fig. 4, curve c, are developed, and these pulses are then supplied to the first frequency divider 41. Essentially, the frequency dividers 41, 42, 43 and 44 are blocking oscillators, the circuits of which will be more particularly appreciated from the showing of Fig. 6. Each of the blocking oscillators or frequency dividers 41, 42, 43 and 44 is interlocked so as to give a resultant frequency division or reduction of 525 to 1. Accordingly, the output from the first frequency divider 41 appears at $\frac{1}{3}$ the frequency of the master oscillator 31, or at 10,500 cycles. The output from the second frequency divider 42 is $\frac{1}{5}$ the frequency of the output of the first frequency divider 41, or $\frac{1}{15}$ the frequency of the master oscillator 31, and consequently is developed at 2,100 cycles. Similarly, the frequency divider 43 reduces the output frequency of the frequency divider 42 by $\frac{1}{3}$ and thus is $\frac{1}{45}$ the frequency of the master oscillator 31, or 420 cycles. Lastly, the frequency divider 44 reduces the output frequency of the frequency divider 43 by $\frac{1}{6}$, so that its output frequency is $\frac{1}{270}$ of that of the master oscillator 31, or 60 cycles. It is, of course, apparent, that the frequency reduction need not necessarily be in the order of $\frac{1}{3}$, $\frac{1}{5}$, $\frac{1}{3}$ and $\frac{1}{6}$, but it is recommended that the lowest reduction ratio be first carried out at the higher frequencies because of slightly greater stability and simplicity of reduction.

It is evident, from what has heretofore been known in the art relating to frequency dividers and sync signal generators, that the last stage 44 of the frequency divider group is supposed to develop output energy precisely at the field frequency of 60 cycles per second. But, to obtain this frequency accurately, a certain auto-

matic frequency control action must be carried out. Accordingly, a portion of the output energy from the last frequency divider 44 is applied to an automatic frequency control unit 45. The wave form output from the last frequency divider 44 of the group has, as indicated, a generally quasi-linear shape as derived from the last stage of the frequency divider and substantially corresponding to that shown by curve d of Fig. 4, and this wave is then caused to beat with the 60 cycle sine wave, such as that shown by Fig. 4e, which is derived from the power supply connected at 47. The result of this beating of the waves of Figs. 4d and 4e together is a heterodyning action which develops a direct current output from the automatic frequency control unit 45 which is directly proportional to the relative phase shift between the two waves—by reason of the quasi-linear form of 4d—and then fed back by way of a conductor such as 48 to the master oscillator 31, so as to control its frequency and maintain it at exactly 31,500 cycles per second, which is 525×60 .

It will be apparent, from the showing of Fig. 1, that the line synchronizing impulses are to be produced continually except for the duration of nine line periods which correspond to the period of time required to produce and transmit the first series of equalizing pulses, the vertical sync pulse interval and the second series of equalizing pulses. Accordingly, it is apparent that the inverted output of the master oscillator 31 may be fed into two separate devices, namely, the line frequency oscillator 35 which operates continuously at one-half the frequency of the master oscillator (that is a frequency of 15,750 cycles) and is synchronized by it through the energy supplied by way of conductor 51. Also, the so-called frequency divider or start-stop system 37, which contains the frequency divider operating at $\frac{1}{3}$ the frequency of the master oscillator 31, is energized from and controlled by the master oscillator 31 by way of energy supplied by conductor 52. The output energy from the frequency divider 37 is in a step-down ratio 1:6 with a pulse output of 5,250 cycles, corresponding to a duration period of three times the time interval between successive line synchronizing pulses, or, in other words, a time duration 3H.

The frequency divider or start-stop system 37, however, does not operate continuously, but is brought into action only during the picture retrace moment, and for this purpose the frequency divider unit 37 is keyed by the output of the frequency divider unit 44 which is developing the 60 cycle output, as shown by wave d of Fig. 4, and this 60 cycle energy is fed to the frequency divider 37 by way of conductor 53. The energy fed to the frequency divider unit 37 by way of conductor 53 is of the general wave form corresponding to curve f, Fig. 4, and it will be noted, for instance, that this keying signal is slightly longer than that actually required and consequently it only serves to actuate the frequency divider at 5,250 cycles, but cannot be used for correct timing or switching action from the line to the frame signals and back again.

In the output of the frequency divider 37 the wave form, as shown by curve g of Fig. 4, appears in the conductor 55 which feeds the energy output from the unit 37 into the square wave generator 57. It will be seen that the wave form g of Fig. 4 includes what appears to be four positive pulses, each of precisely 3H separation, as being built up above the pedestal signal, and it is

these four pulses which are used to trigger the square wave generator 57, whose output is shown by the curve *h* of Fig. 4 and appears to be a square wave voltage which is symmetrically arranged above and below the axis and starts with negative polarity. Special precaution is taken that this polarity is always the same, that is to say, the square wave generator 57 must be designed so that it is of a type which might be called "non-communicative." This voltage then is used to serve as a bias for the master oscillations (as per curve *a* of Fig. 4) which are supplied by way of conductor 58, and consequently the two voltages represented by curves *a* and *h* of Fig. 4 are summed up and applied to the super sync mixer 39.

From what is to follow in the description of Fig. 6, it will be seen that these two superimposed voltages are fed into one of the two pentodes which are in co-operation in the super sync mixer 39 and are used to feed the line signals and the equalizing and the frame signals into the same output line.

To obtain this mixing action, a special relay unit 59 is provided. This relay unit 59 is supplied with energy by way of conductor 61 from the square wave generator 57, and its purpose is that of generating a one-signal pulse of either positive or negative polarity which will be of a duration corresponding exactly to a period of 9H, that is, a period of nine line sync pulses. The single pulse relay 59 is shown in more detail in Fig. 5, and further reference will be made to it, but at this time it should be borne in mind that the single pulse relay 59 is, as above mentioned, of the class termed "non-communicative," that is to say, its pulses are required to have a definite polarity.

The output energy from the single pulse relay 59 is shown in wave form *k* of Fig. 4, and the relay itself is triggered by wave energy which is represented by the curve *j*, also of Fig. 4. This wave form energy is derived from the square wave generator 57 by differentiation and, accordingly, the curve *j* consists of a sequence of four separate pulses alternating in polarity and each of very short duration, which are separated from each other by a time period represented by 3H. Accordingly, the pulses have an alternating polarity sequence of plus and minus.

In order to provide the desired type of signal, the single pulse relay 59 has an inherent quality, as will be appreciated from a further consideration of Fig. 5 later to be discussed in detail, of standing by in an attending or waiting position or state until the first positive pulse of wave *j* arrives. The relay then responds to this one pulse but does not cease operation or fall back until the second negative pulse arrives, and, for the purpose of maintaining a state of operation of this character, electrical inertia is introduced into the circuit of the relay in a manner which will be described particularly in connection with the specific description of Fig. 5.

By the co-operative relationship of the square wave generator and the single pulse relay 59, the super sync mixer 39 produces, at its output, the desired succession of super sync signals which may be impressed upon a predetermined type of transmission line 60, for example, a 10,000 ohm line, but the wave fronts of these resulting signals are generally not sufficiently steep to provide the exact desired signal form. To improve the wave form, a wave shaping amplifier 61 is provided

between the transmission line 60 and the output terminals 62 and 63.

Essentially, as will be seen from the description of Fig. 6, this shaping amplifier includes, primarily, tubes of the pentode class which are particularly capable of re-shaping the wave as desired. Fundamentally, the purpose of the shaping amplifier 61 is to increase the steepness of the leading and trailing edges to a predetermined precision of timing which will correspond to somewhat less than three picture elements (according to RMA standards). At the same time, the amplifier 61 acts as an amplitude clipper, as well as a power amplifier. As a result, approximately a 50 volt pulse amplitude is obtainable in either the positive or the negative direction across a load connected to the terminals 62 and 63 which may be of 1,000 ohms or less, wherein all output signals have substantially equal height and equal slope. This general result is pictorially represented by the curve *m* in Fig. 4.

For the purpose of obtaining the blanking pulses according to the standards pictorially represented by Fig. 1, certain additional tubes and elements are provided. To this end, there is required an additional wave shaping amplifier 65 which is of substantially like nature to the wave shaping amplifier 61 for the purpose of shaping the super sync signals and giving the same output power and voltage. A mixing of the line and frame blanking signals is obtained in a blanking mixer 67, which preferably comprises but a single pentode connected in co-operative relationship with the suppressor grid of one of the amplifier tubes of the shaping amplifier 65.

The blanking mixer 67 acts generally as an amplitude clipper and it receives an input signal of the character generally designated by curve *t* of Fig. 4, which is the output energy from the line frequency oscillator 35. The clipping action takes place, as was indicated by Fig. 1, curve *e*, and the blanking signal can thus be made to precede the super sync because the line oscillator 35 is driven by the inverted wave from the master oscillator, such as that represented by curve *d* of Fig. 2, and this precedes the master wave at a time period equal to the duration of one equalizer pulse or a time period of, say 0.08H.

To provide the proper length of the frame blanking signal and to operate the mixer unit 67, another single pulse relay 69 is provided. This relay 69 is adjusted to give an output pulse of exactly 12H, see curve *n* of Fig. 4, to provide for the picture retrace blanking, and the leading edge of this pulse is intended to be coincident with the leading edge of the first of the equalizers in the super sync. For this purpose, the relay 69 is triggered by the same series of pulses that control the relay 59, which are represented by curve *j* of Fig. 4, and, as was hereinabove stated, this wave is derived from the square wave generator 57 by electrical differentiation. Means next are provided to superimpose a 10% fraction of the super sync signals upon the blanking signals, and thus the transmitters may be modulated over a single channel. The output from the wave shaping unit 65, as shown for instance by curve *p* of Fig. 4, appears at the terminal points 71 and 72.

Reference now may be made to Fig. 6 of the drawings which is a schematic circuit diagram of a complete sync signal generator. As was outlined in reference to Fig. 3, the various tube elements shown in the circuit arrangement of

Fig. 6, have their counterparts in the schematic representations. For the purpose of enabling the tube units readily to be identified in Fig. 6 and compared with the schematic representations of Fig. 3, it will be seen that the combination of the master oscillator 31 and the buffer stage 33 is provided by the tube A and its associated circuit elements.

The frequency dividers 41, 42 and 43 are provided by the blocking oscillator tubes and circuits, generally designated B, C and D. Tube E and its circuit elements co-operate to provide the 60 cycle stage and the frame key signal generator. The automatic frequency control, schematically designated by the unit 45 on Fig. 3, is provided by the tube F and its circuit elements. The line frequency oscillator 35, which is maintained in a state of continuous oscillation, is provided by the tube G and its associated circuit elements. The frequency divider 37, which provides output energy of one-sixth the frequency of the master oscillator, is shown by the tube H and its circuit elements, with the keying action thereon being provided by the tube and circuit E. Tubes I and J and their circuits together represent the square wave generator, generally designated in Fig. 3 as the element 57.

The single pulse relay for developing energy pulses of the duration 9H is schematically represented in Fig. 3 where the element 59 is shown as comprising the tube K and its associated circuit elements. The tube P and its associated circuit elements provides the single pulse relay corresponding to the element 69 of Fig. 3, and is for the purpose of developing the pulses such as shown by curve n of Fig. 4 and which are of a duration 12H. The tubes L and M co-operate with their circuit elements to provide the mixer stages for the super sync, such as shown by the conventional representation 39 in Fig. 3.

From the description to follow, it will be seen that the tube L and its circuit elements develops the equalizer and frame pulses, while the tube M develops the line pulses, and both of these tubes are keyed, in turn, by the single pulse relay K. The tube N with its circuit elements forms the slope shaping amplifier, such as the amplifier 61 of Fig. 3, while the tube O and its circuit elements provides the super sync output stage.

The blanking mixer 67 of Fig. 3 is represented by the tube Q and its circuit elements in Fig. 6, and the tube R, together with the co-operating circuit elements, finds its counterpart in the shaping amplifier 65 of Fig. 3. The tube S functions as the output blanking stage. The tube T functions merely as a rectifier in the power supply line, and the other two illustrated tubes X and Y, in Fig. 6, comprise merely two voltage regulating lamps in the power supply chain.

Now making reference more particularly to the specific circuit of which that disclosed by Fig. 6 represents one form which has been found suitable in its function for the described purpose, it will be seen that the master oscillator A comprises a twin triode tube 75, which, for illustrative purposes, may be a tube of the general type known as the 6F8. The first portion of this tube, comprising the cathode 77, the control electrode 78 and the anode 79, is connected as a blocking oscillator with the tuned plate circuit. The interruption period is provided by a tuned circuit comprising the condenser 81 in series with resistance elements 83 and 85, of which the resistor 83 is (where desired) made variable and thus is capable of providing the necessary tun-

ing. A coupling between the plate circuit and the grid circuit of the first section of the tube is provided by way of the primary and secondary windings of the transformer 87, as indicated.

5 In order to provide for changing the pulse width, for reasons hereinafter to be more fully explained, an additional capacitor 89 is provided and connects to ground at 91. Also connected between the cathode 77 and ground 147 is a 10 cathode resistor 80, preferably of the variable type, which is, in turn, shunted by a condenser 84. The cathode resistor 80, it will be seen, may furnish a convenient means to obtain a rather delicate adjustment of the frequency control in 15 contrast to the more or less coarse adjustment which would be experienced by a variation of the grid leak resistor 83, but which is, of course, entirely practical.

Considering the general arrangement of the 20 oscillator comprising the first half of the tube 75 or the tube A, the coupling transformer 87 has a relatively low stray capacity, so that its natural frequency is generally high, which means a distributed winding should be used; 25 and, on the other hand, the grid leak condenser 81 is of relatively high value. Under these conditions, it can be seen that as the circuit starts to oscillate, it acts somewhat as if the grid coil were tuned by the grid condenser 81, and the 30 grid cathode resistance then becomes substantially negligible for the positive half of the cycle. For the negative half cycle, however, the loading effect of the grid condenser 81 through the tube section comprising the cathode 77, the grid 78 and the anode 89, substantially disappears and the period is greatly reduced substantially to the 35 natural period of the coils, which may be adjusted, furthermore, by the small capacitor 89. It is thus apparent that the output of the blocking oscillator section of the tube 75 is a wave of the general character shown by curves a of each 40 of Figs. 2 and 4, and this may be of the order of approximately 200 volts peak, as indicated.

For the purpose of lengthening the slot width 45 in the vertical signal (that is to provide the 0.08H slot width) it can be appreciated that by eliminating the tuning of the plate coil of the transformer 87 of the master oscillator and increasing the blocking condenser 81, while decreasing or shunting grid and cathode limiters 50 83 and 80, the width of the pulse can be made wider, for example, without in any way departing from the disclosure of the present invention, but by eliminating the tuning provided by the 55 condenser 89 and the resistor 80, which was made small enough to give the plate circuit of the first half of the tube 75 a generally oscillatory character, the output characteristic may be modified. Of course, in this connection also it 60 is desirable to eliminate the tuning of the grid coil.

If, now, it be assumed that the distributed capacity across the plate and grid coils of the 65 transformer 87 is represented by a value C_2 , and this value is substantially negligible, then it becomes immediately apparent that the output pulse energy from the blocking oscillator 75 is of the general wave form shown by the curve a of Fig. 2, except that the first negative portion of the cycle is wider than the positive portion of the cycle. The grid and the plate voltage are equal in amplitude and opposite in polarity and, accordingly, the first half period is made longer than the second half period so that the width 70 of the lower portion of the pulse from the block-

ing oscillator then becomes of a value such that the slots 7 (Fig. 1) are obtained by clipping at level F. At the same time, the narrower pulse shown by the designation 0.04H of Fig. 2, curve a, for instance, which represents the equalizing pulse, is attained by the leading and trailing edges of both pulses in combination with the condition of coincidence, hereinabove explained, when clipping at level E.

This condition of operation is explainable by considering that the grid coil of the transformer 87 is connected in parallel with the blocking condenser 81 through the grid to cathode path 78 and 77 during the first or positive cycle of the grid swing. As the cycle reverses, however, this path in the tube becomes non-conducting and the coil is left alone with its distributed capacity hereinabove assumed as C_2 which is divided equally between the plate coil and the grid coil as the load. Obviously, the natural period of the circuit in the first condition is bound to be longer than the period of the succeeding cycle, and consequently the length of the slot pulse, as shown by curve c of Fig. 2 can readily be changed within predetermined limiting values with regard to the desired width 0.08H by changing the value of the capacity 81 while the repetition frequency of all the pulses can readily be adjusted to the desired frequency by means of adjustment of the leakage resistor 83 or 80.

It is also quite apparent that the back-kick, as shown by the curves of Fig. 2, is substantially exponential of the time constant equal to

$$\frac{L}{2R_i}$$

where L is the inductance of the coil and R_i is the internal resistance of the tube, and, accordingly, it becomes apparent that for very high oscillation frequencies the ratio of the pulse width in the negative direction to the pulse width in the positive direction can be considered as if it were proportional to the square root of the distributed capacity across the primary and the secondary coils divided by the value of the effective capacity 81 which actually may be only a fraction of the grid capacity, due to the interaction of the grid to cathode resistance in series with it. In this instance, the capacity 81 is of relatively large value, for instance, of the order of 10,000 mmf. and, on the other hand, the stray capacity is of the order of about 100 mmf.; this is found to produce the positive pulse equal to about half the width of the negative pulse, with the result that the increased width of the slots in the vertical sync signal, as shown by Fig. 1, is readily obtained from the circuit here shown by providing the master oscillator tube 75 with distributed winding and omitting plate tuning circuit connections.

The blocking transformer 87 comprises two further windings 92 and 93, each of which has an output of approximately one-tenth that of the blocking oscillator, or about 20 volts (assuming a 200 volt output from the oscillator), with the winding 92 being in phase with the plate voltage at plate 79 of the tube 75, and the winding 93 providing an output of opposite phase, as shown by the curve b of Fig. 4 for instance. The output from the winding 92 is caused to appear in the circuits of the tubes J and L, and thus appears directly in the output after suitable clipping and switching. The winding 93, however, is used directly to synchronize the various line and keying oscillators, such as represented by the tubes 95

and 99, functioning respectively as the line frequency oscillator G and the frequency divider H.

The second portion of the master oscillator A, represented by the tube 75, comprises the section including the cathode 101, the control electrode or grid 102 and the plate or anode 103. This section of the tube is connected as a cathode follower stage. The anode or plate 103 is connected to the terminal of the winding of the transformer 87, through which positive voltage is supplied, to energize the plate or anode elements 79 and 103 of the tube. The cathode element 101 is connected to ground potential through the cathode resistors 104 and 106. The control electrode 102 connects back to receive energy, such as that supplied by the blocking oscillator tube control electrode 18. The second half of the tube 75 thus becomes effective in the operation to prevent undesired grouping of the lines in the received picture, and if this buffer section were not present, and if the frequency divider chain formed from tubes B, C, D and E were energized directly from the oscillating system comprising the first half of the tube 75, it will be seen that grouping might occur which amounted to several picture elements so as to disrupt, to some extent at least, the transmission of the vertical lines of the picture.

Referring next to the frequency division provided by the various frequency dividers, such as those represented schematically in Fig. 3 and shown more particularly in Fig. 6 by the tubes B, C, D and E, it will be seen that all the tubes B, C and D are of the general triode type, such as tubes of the 6J5 type. So considered, the first frequency divider thus comprises the tube 105; the second frequency divider the tube 107, and the third frequency divider the tube 109.

The output energy of the second half of tube 75 is cathode coupled to the input of the first tube 105 so that tube 105 is energized by way of the conductor 111 in accordance with the voltage drop across resistor 106. The tube 105 comprises the usual cathode 113, control electrode 115 and the anode or plate 117, which latter element is connected to one winding of the transformer 119 and also to a source of positive voltage as applied to the conductor 121 through appropriate resistors 122 and 123, and high frequencies are by-passed to ground 124 by way of the by-pass condenser 125. The arrangement thus is similar to that by which the tube 75 receives its plate or anode voltage from the conductor 121, and similar to that in which high frequency energy is by-passed to ground from the tube 75 through a similar condenser 125.

In order to tune the period of the blocking oscillator tube 105, provision is made for the use of a grid condenser 127 and suitable grid leak elements 128 and 129, of which the latter is preferably variable in order to provide the necessary tuning. From what was above stated, it appears that the output energy from the tube 105, corresponding to the first frequency divider B, is energized at a period of 10,500 cycles, which will be assumed to correspond to one-third the frequency of the master oscillator tube A or 75. This output energy is fed by way of the coupling provided with the cathode resistor 131, the coupling resistor 132 and the coupling resistor 133, which together form a coupling network of the general type identified as a π network and consist purely of ohmic resistances of low impedance, for instance of the order of about 100 ohms each. The energy output from the first frequency divider

tube B or 105 is thus fed to the second frequency divider tube C or 107 in essentially the same manner as the output from the buffer stage of the tube 75 is applied to the tube 105.

The second frequency divider tube 107 comprises the usual cathode element 135, the control electrode 136 and the plate or anode 137. The plate or anode 137 connects to one winding of the transformer 139, and also connects to the high voltage line 121 by way of resistors 122 and 123, as referred to with regard to the tube 105.

As was explained in connection with the first frequency divider tube 105, this second frequency divider tube 107, which also may be of the general type known in the art as the 6J5, is tuned by means of the condenser 141 operating in conjunction with the resistors 142 and 143, of which the latter is preferably made variable.

The indicated connections to ground 147 are common for a great many tubes in the frequency divider and other portion of the unit.

Output energy from the second frequency divider stage 107 is fed by way of the resistor 149 in accordance with the voltage drop occurring across the cathode coupling resistor 151. The resistors 149 and 151, together with the resistor 153, again form a π section filter, as did the resistors 131, 132 and 133 serving to couple the output of the first frequency divider tube 105 to the input of the second frequency divider tube 107.

At this point it might be well to point out that the π section filter used for coupling offers some advantages in that, by omitting the coupling impedance it is easily possible to pre-set each stage independently, because the subsequent connection affects the natural frequency but very slightly. Further, it is possible to adjust the degree of coupling readily by changing the coupling resistor, and also there is no lag with this type of coupling, and, as another point, the degree of frequency division may be counted readily since both the driving pulses and the reduced frequency pulses appear across the output end of the π network.

The third frequency divider tube 109, which is also preferably of the general type known in the art as the 6J5, serves to reduce the frequency still further, and while the input frequency corresponding to the output of tube 107 is assumed to be 2100 cycles, the output from the frequency from the tube 109 will preferably be 420 cycles. The tube 109 comprises the usual cathode 154, the control electrode 155 and the plate or anode 156 which connects to one winding of the transformer 157. This transformer winding serves to connect high voltage from the conductor 121 to the plate or anode 156 by way of the resistor elements 159 and 160 at the junction of which a condenser 161 is connected to by-pass any possible high frequencies to ground 124. The other winding of the transformer 157 is connected to receive the energy output from the tube 107, and by means of the condenser element 163 and the resistors 164 and 166, of which the latter is preferably variable, the period of the oscillator is adjusted.

In connection with the frequency reduction to the lower frequencies, as provided by the tube 109, it is, however, desirable to tune the circuit including the grid or control electrode 155 by means of the condenser 165 which is connected in parallel to the grid coil of the transformer 157. For the higher frequency stages, such as provided 105 and 107, it has been found that the

natural capacity of the windings is generally satisfactory to provide satisfactory performance, at least with the ordinary way of non-distributed winding, so that in other circuits the tuning condenser 165 may, as a general rule, be eliminated, although it is apparent from what is here stated that tuning of this character may be resorted to in any frequency divider stage.

The output energy from the tube 109 which appears at 420 cycles, is then fed through still another π section filter comprising the de-coupling cathode resistor 167 of the tube 109, the coupling resistor 168 and the grid resistor 169 of the last frequency divider tube E or 171. Thus tube 171 is preferably of the 6F8 type, as is the tube 75, and it uses the first portion thereof as a blocking oscillator section which is of a slightly unusual form in that the storage circuit is connected between the cathode 172 and ground 147 and there is no storage provided in the grid (control electrode) or plate (anode) circuits.

In this connection the energy output of the tube 109 is fed to the grid coil of the transformer 174 and the tuning to control the duration of plate pulse is brought about by means of the condenser 175 in a manner somewhat similar to that explained in connection with the condenser 165 of the tube 109. This condenser 175 connects, as shown, to the control electrode 176 of the first section of the tube 171 whose plate or anode element 177 connects by way of the plate coil of the transformer 174 and a pair of resistors 178 and 179 to the conductor 123, at which the high positive potential appears by way of the connection at the terminal 180.

As was explained in connection with all of the other frequency reducing tubes, a condenser 181 connects between the resistors 178 and 179 and ground 124 to by-pass any high frequencies. Output energy from the first section of the tube between the cathode 172 and ground 147 is of quasi saw-tooth character with a positive peak such as shown by curve d of Fig. 4. This energy is caused to appear across the cathode resistors 183 and 184, of which the latter is preferably variable and used to determine the repetition frequency of the system, and is fed by way of a conductor 186 to a phase control tube 190 which, for example, may be of the general type known in the art as a 6J7. The condenser 181 serves to by-pass any high frequencies to ground.

The quasi saw-tooth wave, as it appears in the conductor 186 corresponding to the output of the first half of the tube 171, is to serve the purpose of automatic frequency control which is provided by beating this output with the 60 cycles per second of the power supply frequency which is connected at the terminals 192 and 192', and this is possible because there is a particular linear relationship between phase displacement and the D. C. output in such a wave. Further, in connection with the tube 171, the output from the plate or anode element 177 is preferably of a pulse nature and is adjusted to be of a duration of approximately 11H, as was indicated by curve f of Fig. 4, and this adjustment of the length of the pulse is, as above stated, brought about by tuning in the grid circuit by means of the condenser 175 in series with a resistor 192 and the grid coil of the transformer 174.

It was already explained that it is desirable that this signal output for the plate 177 of the tube 171 shall have a duration of slightly more than 9H but less than 12H as this is the char-

acter of signal required to operate the square wave generator for just three cycles of 3H duration, but no longer. The second portion of the tube 171, comprising the cathode 193, the control electrode or grid 194 and the plate or anode 195 is, generally speaking, connected as a cathode follower. It draws current which is cut off for the duration of the pulses, and thereby an inherently flat top level of the key signal is secured for a time duration of approximately 11H. This keying signal is developed across the cathode resistor 196 and serves to operate the second half of the frequency divider tube 99, which is for the purpose of reducing the frequency to one-sixth that of the master oscillator 75.

Simultaneously, the plate current of the second half of this tube 171 is applied to the relay tube 200 to make it of a non-commutative character. This effect is obtained by feeding this output energy through the conductor 201, so that it flows through an appreciable portion (the part 279) of the plate resistor 202 and 279 for the tube 200, and this results in a definite unbalance of this relay during certain predetermined periods and it is not until the emission in the tube 171 is cut off that the balance in the relay tube 200 is re-established, as will become apparent from a further discussion of this tube in what is to follow. The effect is, however, that the relay tube 200 shall be in a predetermined and definite state with regard to operation when the first directional pulse from the square wave generator and triggering tube 204 reaches it, as will later be explained and as is set forth in companion application Serial No. 445,253, filed May 30th, 1942, which is entitled "Electronic relays."

Now, referring more particularly to the automatic frequency control tube 190 which receives energy of quasi saw-tooth character on its #1 grid 206 from the conductor 186 by way of the time constant circuit 207 comprising the parallel capacity 208 and resistance 209, it will readily be appreciated that the impressed energy is a saw-tooth voltage of substantially 60 cycles. Consequently, the amount of direct current which the tube 190 can pass will depend upon the instant at which the tube is made conductive by a pulse derived from the 60 cycle power supply line assumed to be connected to the terminals 192 and 193 being supplied to the #2 grid 210 by way of the transformer 211 and the resistance capacity circuit 212.

Normally, the #2 grid (screen grid) of the tube 190 is negative and no plate current flows through the tube. However, during the positive swing of the power supply frequency connected to be supplied through the transformer 211, it is apparent that the tube 190 may be made conductive for a short instant. The necessary negative bias superimposed between the 60 cycle per second voltage and the screen or #2 electrode 210 is provided by the resistance-capacity circuit comprising the resistance 213 and the capacity 214 which provides a self-biasing effect. It is evident that the nearer the conductor period comes to the positive peak of the #1 or control grid swing the more current will flow, as determined by the quasi saw-tooth applied thereto. Any A. C. components in the output of the tube 190 may readily be filtered in the filter chain comprising the condensers 216 and 217, each connecting to ground 147 and having the smoothing resistance 218 connected therebetween so that the resulting direct current output may be measured by means of the meter 219 (conventionally represented) and fed back by 75

way of the conductor 220 through the resistor 221 to be applied to the control electrode 78 of the master oscillator 75 where it is caused to vary the bias on the control electrode and thereby control the operational cycle.

It is apparent that in operation the polarity of the variations should be rendered such that the automatic stabilization of the frequency is obtained within a very small range of direct current, for example, one millampere, and this permits the control of a wider frequency variation than ever is to be expected in practice, even under adverse conditions.

By means of the variable resistors 83 (coarse) or 80 (fine) connected to the control electrode 78 of the master oscillator tube 75, the direct current output from the tube 190 is adjusted so as to appear at approximately the center of the scale of the meter 219, so that positive and negative variations of the power line frequency are equally well compensated. Any high frequencies induced into the secondary winding of the transformer 211 are readily by-passed to ground by means of the bypass condenser 222.

The tubes 99, 204 and 200 respectively serve to provide the necessary square wave bias so as to obtain equalizing and frame signal clipping within a mixer tube 225 (also preferably of the general type known as a 6J7) which will be later explained in further detail. The tube 99 is arranged to function as a frequency divider tube and is essentially for the purpose of providing a frequency output corresponding to one-sixth the frequency of the master oscillator 75.

In its broadest aspect, the tube 99 is connected in the same manner as was disclosed for the frequency divider unit set forth and claimed in my co-pending application Serial No. 433,289, filed March 4, 1942, entitled Frequency divider (RCA Docket 21,107). Energy to drive the frequency divider unit 99 is derived from the coil 93 associated with the transformer winding 81, and the wave energy (as shown by curve Fig. 4b for example) induced into this coil is then fed by way of a time constant circuit comprising the parallel combination of resistor 227 and condenser 228 to the control electrode 229 of tube 99.

The time constant of the resistance capacity circuit 227-228 is essentially such that operation takes place at approximately one-sixth the frequency of the master oscillator 75 and, as was above explained, when the energy from the tube 75 is fed to the control electrode 229 of the tube 99 it is supplied in inverted polarity, as was indicated for instance by curve b of Fig. 4. It is apparent that the inversion of polarity, in effect, gains time so that the switching mechanism is ready to supply the required bias on the mixer tube 225 prior to the time the first equalizer pulse is applied by way of the condenser 231.

The frequency divider tube 99 is operated in a start-stop manner, and the bias on the control electrode 232 of the second half of the tube is made highly positive as long as the plate current in the second half of the tube 171 is not interrupted. The cathode output of the tube 171, as it appears across the resistor 196, is supplied to the control electrode 232 by way of the conductor 233, but the cathode element 234 of tube 99, acting as a cathode follower stage, is biased highly positive, and the plate current flowing in the first half of the tube 99 comprising the cathode 234, the control electrode 229 and the plate or anode element 235 is arranged to be cut off throughout the cycle of picture scanning corresponding to the time

period 11, as shown by Fig. 1. However, as soon as the current in the second half of the tube 171 is cut off by the field frequency pulse of a duration 11H, as shown by curve *f* of Fig. 4, the grid bias applied to the control grid 232 of the second half of the tube 99 is reduced and the cathode 234 follows. Consequently, the first half of the tube 99 comprising the cathode 234, the control electrode 229 and the anode or plate 235 comes into action as a frequency divider and provides an output at a frequency of one-sixth the frequency of the master oscillator, or at 5250 cycles, at the conductor 236 and across the resistor 237. Consequently, it is apparent that a series of four positive pulses with intermissions of a period 3H will appear across the resistor 238 connected to the anode or plate 239 of the second half of the tube 99, and it is further apparent that no more than four such pulses can be produced because, in the period between 9H and 12H (see Fig. 4, curve *f*) the plate current in the second half of the tube 171 is restored and the action of the tube 99 thereby ended.

In companion application Serial No. 445,253, filed May 30, 1942, entitled Electronic relays, it has been explained how square waves may be produced by two triodes in special connection, as shown by the tubes 204 and 200 under the influence of positive triggering pulses.

The arrangement of Fig. 4 of the last mentioned specification, showed generally an arrangement closely related to that embodied in the use of the tube 204 as the driver tube or the square wave generator trigger tube, and the tube 200 as the relay tube and amplifier tube. It is, however, to be noted that in contrast to the arrangement shown by the last mentioned co-pending application, a tube of the general type known in the art as the 6F8 (with separate cathodes) is substituted for the form of relay tube previously shown, so that adequate power output may be delivered for the action of the mixer channel including the tubes 225 and 226 by cathode-follower coupling.

Output energy from the frequency divider unit or tube 99 is fed to the control electrodes 241 and 242 of the driver tube 204 by way of the coupling condensers 243 and 244 respectively. This tube has its cathode element 246 appropriately biased relative to ground 247 by means of a bias resistor 248 in accordance with potential supplied by the resistor 249 from the positive potential conductor 250 which also supplies plate voltage for the plate or anode elements 235 and 239 of the tube 99 through the resistor 251.

The control electrodes 241 and 242 of the driver tube are connected with the control electrodes 253 and 254 of the relay tube 258, so that the condenser 243 and the resistor 255 form one time constant circuit, and the condenser 244 and the resistor 256 form the second time constant circuit, both time constants being the same.

The cathode elements 257 and 258 of the tube 200 obtain bias relative to ground 247 by way of resistors 259 and 260 connecting through a common resistor 261 to ground, with a condenser 262 by-passing high frequencies to ground around the resistor 261. Output energy from the first half of the relay tube 200 flows from the plate or anode 263 thereof by way of the conductors 265 and 267 and the coupling condensers 268 and 269 to the relay tubes 271 and 272 (or P and K) respectively. Also from the cathode 258 of the second half of the relay tube 200 output energy is derived in accordance with the voltage drop

across the cathode resistor 260, and this output, as before stated in the discussion of Fig. 3, flows through the coil 92 and the coupling condenser 231 to the control electrode 273 of the mixer tube 225, so that at the control electrode 273 voltage waves corresponding to the curve *a* of Fig. 2 (the frequency output of the master oscillator 75 starting with negative polarity) and curve *h* of Fig. 4 are combined. A leak resistor 274 connects the control electrode 273 to the cathode 275 of the mixer tube 225, and the cathode 275 is biased relative to ground 247 by the biasing resistor 277.

Thus, it can be seen that with the input voltage applied to the grid or control electrode 273 of the mixer tube 225 determined in accordance with the voltage drop across the cathode resistor 260, as well as by way of the connection to the coil 92 into which impulses starting with negative polarity, as shown by curve *a* of Fig. 2, are induced from the master oscillator, the clipping level will be as indicated by the line E in Fig. 2a.

In connection with the square wave generator units 204 and 200, it was above pointed out that under normal circumstances it might be possible for the tube 200 to become conducting, so that one or the other of the two halves of the tube would draw current when the first trigger pulse arrives. However, for the purpose of developing a synchronizing signal generator arrangement, it is essential that it be determined which of the two halves of the relay tube 200 shall conduct, and, to this end, an unbalanced condition is provided by causing the output current from the second half of the tube 171 to flow through a portion 279 of the plate resistors 202 and 279 of the second half of the tube 200. Once the current flowing through the second half of the tube 171 is cut off, the relay tube 200 is balanced, in that the plate resistor 280 for the first half of the tube is made equal to the series resistance provided by the series combination of the resistors 202 and 279.

It thus becomes apparent that the relay tube 200 will always start in operation with the second half, comprising the cathode 258, the control electrode 253 and the plate or anode 281 conducting, and in this way the curve *h* of Fig. 4 is obtained in such a way that there is provided an output pulse which is symmetrically positioned about the axis with no D. C. component, in contrast to the normally expected D. C. component which would ordinarily appear with D. C. coupling.

Reference now may be made to the mixer tubes 226 and 283 which each have their #1 grid or control electrodes 285 and 287 respectively connected to the output electrode 289 and the plate resistor 290 of the second half of the line frequency oscillator tube 95. Thus, connections are made to the mixer tube 226 via the conductors 291 and 292 and the coupling condenser 293, and to the blanking tube mixer 283 by way of the conductor 291, the resistor 294 (used to drop the voltage) and the coupling condenser 295.

The grid leak resistor 296 is connected between the control electrode 285 and the cathode 291 of the mixer tube 226, and likewise the leak resistor 298 is connected between the grid or control electrode 287 and the cathode 299 of the mixer tube 283, and each of these resistors is of relatively high value. In each case, automatic grid bias of such a magnitude is built up in the tubes that only the positive peaks of the line frequency impulses, forming the output from the tube 95, are amplified in the super sync mixer tube 226.

The blanking tube mixer 283, however, has included between the conductor 291 and the coupling condenser 295, through which the output of the tube 95 is supplied, the series resistor 294 hereinabove mentioned which serves to limit the grid current and consequently results in a clipping action taking place within the tube 283 at a lower level. This, of course, results then in the production of a longer duration pulse from the tube 283 than is obtained from the tube 226 as would be expected from the showings of curves *e*, *f* and *g* respectively of Fig. 2, which diagrammatically illustrate the production of the line blanking and the synchronizing pulses from the common pre-shaped input signal.

Suitable positive voltage for the mixer tubes 225 and 226 is supplied to the plate or anode elements 300 and 301 thereof by way of the high voltage conductor 250 and the resistors 303 and 304 with the condenser 305 serving to by-pass any high frequencies to ground 247. Similarly, the line frequency oscillator tube 95 and the relay tube 272 each derive positive plate potential by way of the conductor 307 connecting with the conductor 250 and the plate resistors, as indicated, so that plate potential is supplied to the first half of the tube 95 by way of the resistors 308 and 309 with the by-pass of high frequencies to ground 247 being provided by the condenser 310, and plate potential to the second half of the tube 95 is then provided by the plate resistors 308 and 290 hereinabove mentioned. Likewise, plate potential for the anode or plate element of the relay tube 272 is provided from the conductor 307 by way of the resistor 311 and the resistor 312 for the first half of the tube, and the resistor 313 for the second half of the tube.

The general circuit arrangement of the single pulse relays 59 and 69 of Fig. 3 are shown more particularly by the tubes 272 and 271 and associated circuits respectively, used to control the operation of the mixing tubes 225 and 226 as well as the shaping amplifier 317 later to be described. Further, the single pulse relay arrangement shown particularly by the tubes 272 and 271 respectively, and their associated circuit elements form the subject matter of a separate co-pending application identified as Single pulse relay, filed July 30, 1942, Serial No. 452,922.

In some senses the relay arrangement 272 (and consequently also the relay 271) tends to function as a multi-vibrator, but is of a somewhat different form than the well known multi-vibrator in that it is of the type which may be stated to be A. C.-D. C. coupled.

The second half of the single pulse relay tube 272, which includes the cathode 319, the control electrode 321 and the plate or anode element 323 is A. C. coupled through the condenser 325 and the bleeder resistor combination comprising the resistors 326 and 327, so that the energy from the second half of the tube is fed back to the control electrode 329 of the first half of the tube which includes also the plate or anode element 331.

The cathode 319, which serves as the cathode for both halves of the tube 272, is suitably biased relative to ground 247 by means of the cathode bias resistor 332. The first half of the tube 272 comprising the cathode 319, the control electrode or grid 329 and the plate or anode 331 is connected to the second half of the tube by way of the bleeder resistor combination 334 and 335 with a connection being made from the control

electrode 321 and the junction of the resistor 334 to ground by way of the resistor element 335.

The general arrangement of the system thus disclosed is one which operates in such a manner that it can develop but one output pulse at a time, and the duration of the operational cycle may be readily controlled by the pre-arranged time constant determined by the capacity 325 and the sum of the resistor values of the resistors 326 and 327, as well as the general tube constants. If there are no triggering impulses applied to the system by way of the conductor 267 connecting to the output of the relay tube 200 and supplying energy by way of the condenser 269 (which is quite small), the relay arrangement is maintained in a state where the left hand half of the relay tube 272 is conducting and the second half of the tube is blocked off because the grid or control electrode 329 is connected to the cathode 319 across the resistor 327. Consequently, the output pulse will be non-commutative.

If reference is now made, however, to the curves of Fig. 5, and first to curve *a* thereof, it will be seen that the relay device may be triggered by the arrival of a pulse of negative polarity, such as that shown by the first pulse, reading from left to right, in curve *a* of Fig. 5. Normally, the relay tube 272 would trigger in the opposite direction by the arrival of the second pulse shown by second curve *a* of Fig. 5, which second pulse is of positive polarity, under conditions where the time constant of the operation was of a time order comparable to the interruption period between the first and second pulses. However, provision can be made whereby the relay tube 272 will not follow the first positive pulse received subsequent to the receipt of the operation initiating negative pulse, but rather the relay will be triggered in the opposite sense by the arrival of the second positive pulse following the controlling negative pulse and this delay can readily be established by lengthening the time constant provided by the system to a value approximately twice as long as the time between the first negative and the first positive pulse.

If these conditions are followed, then the relay will switch back to its normal state (that is, the second half non-conducting and the first half conducting) upon the arrival of the second positive pulse (as in curve *a* of Fig. 5), following the operation initiating negative pulses, and for this purpose the time constant of the relay tube arrangement 272 is made to coincide with a time period of operation of the order of 9H (see Fig. 1).

The relay tube 271 is of the same general nature as the relay 272 and, in its normal state, the second half of the tube, comprising the cathode 339, the control electrode or grid 340 and the plate or anode 341, does not pass current, so that there is no energy feedback by way of the condenser 343 and the resistor elements 344 and 345, at the junction of which resistor elements the control electrode 346 of the first half of the tube is connected, as indicated.

The plate or anode 341 of the first half of the tube connects back to the control electrode or grid 340 of the second half of the tube by way of the D. C. coupling resistor 349 and to ground 247 by way of the resistor element 350, as was shown for tube 272. Also, as was the case with the relay tube 272, a common cathode bias, relative to ground 247, for both halves of the tube

is provided by the cathode resistor 351 which, if desired, may be by-passed for high frequencies by the capacitor 352.

The relay tube 271 essentially is intended to act as a frame blanking commutator and, accordingly, the time constant is so chosen that its period of operation, as determined by the capacity 343 and the sum of the resistors 344 and 345, should be longer than for the relay 272 and preferably of a time period of the order of about 12H, so that the condenser 343 is usually somewhat larger than the condenser 325 of the relay tube 272.

In order that the relay tube 271 shall not operate to render the first half non-conducting upon the arrival of the second positive pulse (such as that shown by curve *a* of Fig. 5) but at a subsequent pulse, it is understood, of course, that the relay tube 271 is controlled from the same source provided by the tube 200 as is the relay tube 272.

Wave forms of the cathode and plate outputs of the single pulse relays 272 and 271 are generally shown by curves *b*, *c* and *d* respectively of Fig. 5, and from these pulse indications it will be seen that the sync pulses are not flat topped but nevertheless show a linear increase and decrease respectively in amplitude plotted against time. This is due to the interaction of the two plate currents flowing in the tubes 272 or 271 through the common cathode resistors 332 and 351 and acting in opposite senses thereupon.

In order to obtain a pulse output of desired wave form and height, the plate and cathode pulses may be mixed in a common resistive network which is provided by means of the resistors 353 and 354 for the first half of the relay tube 272, and the resistors 355 and 356 for the second plate circuit of the same tube, so that the output from the first half of the tube, as it appears in the conductor 357, shall coincide approximately with the wave form *e*₁ of Fig. 5, and the output energy as appearing in the conductor 358 shall be approximately of the wave form as shown in *e*₂ of Fig. 5, by selecting the appropriate and critical tapping point across the respective bleeder resistors last named. In this way, the pulse output from the first half of the relay tube 272, as it appears in the conductor 357, is always positive in sign, and the pulse output from the second half of the tube 272, as it appears in the conductor 358, is always negative in sign.

By appropriate selection of voltage for the plate supply of the tubes 271 and 272 at a value of the order of about 200 volts, both of these outputs may be made of approximately 50 volts by an appropriate choice of circuit constants.

The arrangement of the relay tube 271 is approximately the same as that disclosed for the tube 272, except that the output energy from the second half of the tube, as it appears in the conductor 361, is of negative sign, and, like the arrangement of the relay 272, the tube functions to produce relay action of a predetermined time duration in response to input voltages which exceed a predetermined value, or to the receipt of input pulses.

Reference now may be made to the line frequency oscillator tube 95 which is connected to receive energy at a frequency of the master oscillator tube 75 as such energy is picked up in the coil 93 associated as an independent winding upon the main oscillator transformer 87. The pulse of energy as it appears in the winding 93, and as it is fed by way of the conductor 363 to control the control electrode 365 by way of the

coupling condenser 366 is initially of positive polarity, as shown for instance by curve *b* of Fig. 4.

The general arrangement of the line frequency oscillator tube 95 is substantially like that disclosed and claimed in my co-pending application Serial No. 433,289, filed March 4, 1942, where reference may be made particularly to Fig. 2 thereof, for instance. In the arrangement here-
10 disclosed, the first half of the tube 95 comprising the cathode 367, the control electrode 365 and the plate or anode 368 feeds its energy by way of the potential divider provided by the resistors 369 and 370 so as to supply energy to the control electrode 371 of the second half of the tube 95.

The cathode 367 is appropriately biased to ground 247 by way of the cathode resistor 373 and the second half of the tube 95, as was explained in the last referred to co-pending application, acts as a cathode follower stage so that through the appropriate choice of the time constant and the tube operation as well as the circuit elements provided by the condenser 366 and the leak resistor 375, the tube 95 may be caused to produce a pulse output from the plate or anode 289 of the second half thereof which will appear in the output conductor 291 in positive sign, so as to be applied by way of the coupling condenser 293 to energize the control electrode 285 of the mixer tube 226. This same mixer tube 226 has energy pulses of negative polarity (like pulses of curve *e*₂ of Fig. 5) supplied to the #3 grid 376 through the coupling condenser 377.

The output pulses from the relay tube 272, which are of positive sign as shown by curve *e* of Fig. 5, and which appear in the conductor 357, are applied directly to the #3 grid 379 of the mixer tube 225. Thus, it can be seen that with the mixer tubes 225 and 226 connected together with a common plate supply and a common plate output circuit, output energy can be fed to the shaping amplifier tube 390 across the resistor 391, so that this energy is then applied between the #1 grid 392 and ground 247. The cathode 394 of the tube 390 is appropriately biased relative to ground 247 by the bias resistor 395 and any high frequencies may be by-passed, as desired, by the by-pass condenser 396.

It is, of course, apparent that the circuit parameters of the tubes 225 and 226 may be adjusted in such a way that the energy wave form applied to the grid or control electrode 392 of the shaping amplifier tube 390 is of the general wave form corresponding to that diagrammatically represented, for instance, by curve *m* of Fig. 4 (only with "round" edges), and this is determined, in turn, by the relative polarity of the energy impressed upon the #1 and #3 grids of the mixer tubes 225 and 226 which is caused to appear in the wave form fed through the resistor 391.

The operation of the wave shaping amplifier tube 390 which, for instance, may be of the general type known in the art as the 6AC7, is such as to increase the steepness of the leading and trailing edges of the pulses applied thereto, and will be further explained in connection with a discussion of the wave shaping tube 317, which is also preferably of the same general type as the tube 390.

The output energy from the second half of the relay tube 271 is supplied, as above stated, by way of the conductor 361 and the coupling condenser 398 to the #3 grid 399 of the shaping amplifier

317, so that this energy appears across the resistor 401 and is applied between the #3 grid 399 and the tube cathode 402, which latter element is biased relative to ground 247 by the cathode bias resistor 403. Similarly, the output from the blanking tube mixer 283, as it appears in the plate circuit of this tube and in the conductor 405, is supplied to the #1 grid 407 by way of the time constant circuit comprising the resistor 408 and the capacity 409 and caused to appear across the leak resistor 410 connected between the #1 grid 407 and ground 247. Thus, output energy pulses from the relay tube 271, which are of a duration approximately 12H, as shown by curve *n* of Fig. 4, are applied in the negative sense to the #3 grid 399 of the shaping amplifier tube 317 and the output energy pulses from the blanking mixer 283 are applied simultaneously to the #1 grid 407 of the shaping amplifier tube 317.

Referring back now to the relay tubes 272 and 271, it will be appreciated that with the first half of each tube normally conducting prior to the receipt of the triggering pulses as shown, for instance, by curve *a* of Fig. 5, the potential appearing in conductor 351 and applied to the #3 grid of the tube 225 is negative with respect to the potential which this grid will assume when the first half of the tube 272 ceases to draw current as of the time when the first negative pulse is impressed upon the control electrode 329 by way of the coupling condenser 269.

Likewise, the #3 grid 316 of the tube 226 is normally held at the potential of its cathode 291 by virtue of the connection thereto through the grid leak resistor 413, and then when the relay 272 is triggered so that current flows through the second half of the tube including the plate or anode 323, the control electrode 321 and the cathode 319, a negative impulse such as shown by curve *e2* is fed by way of conductor 358.

The signals appearing in the output of the second half of the tube 271 are, as above stated, of the same general character as the output signals of the second half of the tube 272, and, accordingly, the tube 271 is arranged to control and operate the shaping amplifier 317 by virtue of the impulse applied through the condenser 398 to the control electrode 399.

In order that the mixer tubes L and M and Q and their associated shaping amplifiers N and R may be properly operated to derive the desired form of signal pulse, the time constant of the relay tube 272 is made of the order of 9H while for the relay tube 271 this time constant is lengthened to the order of 12H, although the relay tube 271 is controlled from the same source as the relay 272, but by lengthening the time constant the relay 271 will not operate as does the relay 272 upon receipt of the second positive pulse, as shown by curve *a* of Fig. 5, but will change its state of operation in accordance with the adjustment and size of the condenser 343. After the sync signals and the blanking signals have been mixed in their respective channels, and as they appear individually across the load resistors 304 of the tubes 225 and 226 and the load resistor 415 of the tube 283, the signals are then fed into high gain tubes, such as the shaping amplifiers 390 and 317 respectively for the sync and the blanking signals.

As was above pointed out, the amplifiers 390 and 317 are primarily for increasing the steepness of the leading and trailing edges of the signal pulses applied thereto, and this is readily done by using a high gain tube, for instance, one

of the type known in the art as the 1852 or the 6AC7, although, of course, any other suitable form might be substituted providing the functions are as desired. It thus becomes apparent that across the plate resistor 415 of the tube 283 only the line blanking signals appear, as the complete blanking sequence has not been provided up to this point of the circuit. The addition of the frame blanking impulses is provided by the use of the first blanking-shaping amplifier tube 317 which is used in a sense as a modulator by applying the blanking impulses upon the #3 grid 399.

Referring now more particularly to the sync signal channel, the output signals from the mixer tubes 225 and 226 are applied through the circuit comprising the parallel combination of the resistor 415 and condenser 417 so as to be impressed upon the control electrode 392. The parallel combination of the resistor 415 and the condenser 417 acts, in general, as a low frequency compensator and corrects the influence of the plate filter combination comprising the resistor 303 and the condenser 305 which becomes slightly charged during the frame impulses. Generally speaking, the effect of this low frequency emphasis is cancelled when the circuit comprising the resistance 415 and the condenser 417 is so designed that it has a time constant substantially equal to that of the plate filter combination of the tube. In addition, the arrangement provides means by which positive bias may be applied to the grid or control electrode 392 of the tube 390, and this has some advantageous effect in reducing ripple and hum underlying the basis of the pulse sequence introduced by the plate supply to the tubes 225 and 226. Output energy from the tube 390 is then fed by way of the conductor 419 and coupling condenser 421 so as to be impressed upon the amplifier tube 425 which is provided with the usual leak resistor 427. The shaping amplifier tube 390 is adapted to emphasize the high frequencies by reason of the capacity 395 being arranged to shunt the degenerative cathode resistor 395. The tube 425 is coupled to receive the output from the shaping tube 390. For this purpose, the signal output from the tube 390 is fed from the plate 429 through the conductor 419 of the coupling condenser 421 to be impressed upon the control electrode 431 of the tube 425, and then appears in the output circuit of this tube across the output resistor 433. The tube 425 is primarily for the purpose of providing power and polarity inversion. The tube 425 delivers positive super sync by cathode follower action across its cathode resistor 433, and simultaneously delivers negative super sync of equal amplitude across its plate or output resistor 433. Each, however, represents a slightly higher impedance and makes a separate matching tube often desirable, if it is desired to connect this output upon a low impedance line.

With regard to the blanking signals as amplified in the shaping amplifier 317, it will be noted that the degenerative effect of the cathode resistor 403 is substantially overcome through the inclusion of a by-pass condenser 435 similar to the condenser 376 used with the tube 390 to by-pass its cathode resistor.

For the purpose of improving the high frequency response in the shaping amplifier 317, a peaking coil 431 is included in the plate circuit, and the output from the tube 317 is then fed across the load resistor 439 through the conductor 441 and coupling condenser 442 to be impressed upon the control electrode 443 of the out-

put blanking amplifier tube 445. The output blanking amplifier 445, like the output sync amplifier 425, is also preferably of a reasonably high gain type tube and functions in a manner quite related to the tube 425 just discussed and might be described as a power matching tube.

Signal energy output from the tube 445 is derived from the plate or anode element 447 across the load resistor 448 and also across the cathode resistor 449 which serves to bias the cathode 450 relative to ground. A similar bias is applied to the cathode 451 of the tube 425 by way of the cathode resistor 453.

In order that either positive or negative synchronizing and blanking pulses may be derived from the blanking output amplifier 445 and the sync amplifier 425, suitable terminal points 460 and 462 are provided for the tubes 445 respectively to obtain negative polarity blanking and sync signals, and terminal points 464 and 466 are provided respectively for obtaining the positive polarity signals which, as is apparent, are obtained across the cathode output resistors 449 and 453 respectively.

Under these circumstances, the ends of the conductors 467 and 468 respectively may be connected on the one hand to terminals 460 and 462 for cases where the negative blanking and sync signals are desired, or, as indicated by the dotted line, the connection between the ends of the conductors 467 and 468 to the terminal points 464 and 466 respectively. Where it is desired that the blanking and sync pulses be of a positive polarity, connections may be made by the terminal points 464 and 466, so that the outputs supplied to these conductors are taken respectively across the cathode output resistors 449 and 453 of the output blanking and output sync amplifier tubes 445 and 425 respectively. These signals are then fed through the loading resistors 471 and 473 to be supplied from the terminal point 475, at which point it is apparent that there is a superposition of both the blanking and the sync pulses so that there is obtainable at the terminal point 475 a pedestal signal with adjustable super sync pulse combined.

Power for operating the complete system is derived by way of the transformer 477, for instance, whose primary winding 478 is connected to terminal points 479 and 480 which are, in turn, connected to a suitable source of power supply energy not shown. The secondary winding 481 of the transformer 477 is connected in known manner to the plate elements 482 and 482' of the full wave rectifier tube 483. The midpoint of the transformer secondary 481 is connected to ground 247 in known manner.

Suitable smoothing is provided by way of the shunt condensers 485, 486 and 487 and the series resistors 488 and 489 which connect to the positive or cathode terminal 490 of the rectifier tube. For the purpose of providing further stabilization of the output voltage from the system, a pair of series connected voltage regulator lamps 492 and 493 is provided in well known manner.

It can be appreciated, from the connections shown, that the positive voltage for the various tubes of the system is derived from the positive voltage conductors 495 and 496 respectively which are arranged to connect with the various conductors indicated as supplying voltage to the various tubes of the arrangement and also to the terminal points such as 180, which connection is not shown in detail for the sake of simplicity of showing. In this connection, it may be pointed

out that a regulated power supply is generally required for the timing and correcting circuits only, but, as a general rule, not for shaping and power amplifiers.

What I claim is:

1. A television synchronizing signal generator comprising a master oscillator for generating steep front asymmetric impulse energy waves of a predetermined frequency and impulse duration, clipping means for deriving each of a plurality of separate energy waves from the master oscillator by clipping at predetermined separate amplitude levels of the impulse energy waves, frequency reducing means to derive energy from the master oscillator at a sub-harmonic thereof, clipping means for deriving from the reduced frequency waves energy at each of a plurality of predetermined energy levels, and means to combine the several produced energy waves.

2. A synchronizing signal generator for interlaced television comprising a master oscillator for generating steep front asymmetric impulse energy waves of a predetermined frequency and impulse duration, clipping means for deriving equalizing and frame synchronizing energy waves from the master by clipping the asymmetric energy output waves at predetermined separate amplitude levels, means to develop a phase-advanced energy wave from the master oscillator output, frequency reducing means to develop line frequency synchronizing signals, means to control said frequency reducing means by said phase-advanced energy wave to derive energy under the control of the master oscillator at a sub-harmonic frequency thereof, clipping means for deriving from the reduced frequency waves energy at each of a plurality of predetermined energy levels of the said wave, and a combining circuit to combine the several developed signals.

3. A synchronizing signal generator for interlaced television comprising a master oscillator for generating steep front asymmetric impulse energy waves of a predetermined frequency and impulse duration, clipping means for deriving each of a plurality of separate energy waves from the master oscillator output by clipping said output energy waves at predetermined separate amplitude levels, means for deriving a phase-advanced energy wave from the master oscillator output, frequency reducing means, means to energize the frequency reducing means under the control of the phase-advanced energy wave to derive energy at a sub-harmonic frequency of the master oscillator, clipping means for deriving from the reduced frequency waves energy at each of a plurality of predetermined energy levels of the said waves, and means to combine the several produced energy waves.

4. A television synchronizing signal generator comprising a master oscillator for generating steep front asymmetric impulse energy waves of a predetermined frequency and impulse duration with predetermined width in positive and negative portions of the cycle, clipping means for deriving each of a plurality of separate energy waves from the master by clipping at predetermined separate amplitude levels of the impulse energy waves, frequency reducing means to derive energy from the master oscillator at a sub-harmonic thereof, clipping means for deriving from the reduced frequency waves energy at each of a plurality of predetermined energy levels, and mixer means operating under the control of the master oscillator to combine the several energy waves developed.

5. In apparatus for developing energy for synchronizing interlaced television systems, a source of oscillatory energy of a frequency F , where F represents the picture line frequency multiplied by the number of picture fields per picture frame, means to generate from said circuit of oscillatory energy other energy at frequencies F/N , F/M and F/AM , where N represents the number of picture lines per picture frame, M represents the number of picture fields per picture frame and A represents a whole number greater than unity, a square wave generator and means to control said generator from the energy developed at the frequencies F/AM and F/N , a pair of single pulse relay devices, means to control the operation of the single pulse relay devices from the output of the square wave generator, a plurality of separate mixer tube circuits, means to supply energy output from one of the single pulse relays and also energy at the frequency F/M to one of the mixer circuits, means to supply energy output from the other single pulse relay combined with frequencies at frequencies F and F/M and the output of the square wave generator to control the other of said mixer tube circuits, wave energy shaping circuits connected to each mixer tube output circuit, and means to combine the outputs of the wave energy shaping circuits.

6. In apparatus for developing energy for synchronizing interlaced television systems, a source of oscillatory energy of a frequency F , where F represents the picture line frequency multiplied by the number of picture fields per picture frame, means to generate from said circuit of oscillatory energy other energy at frequencies F/N , F/M and F/AM , where N represents the number of picture lines per picture frame, M represents the number of picture fields per picture frame and A represents a whole number greater than unity, a normally blocked square wave generator, means to unblock said square wave generator under the control of the energy developed at the frequency F/N , means to energize the square wave generator during its unblocked periods by energy at the frequency F/AM , a pair of single pulse relay devices, means to control the operation of the single pulse relay devices from the output of the square wave generator, a plurality of separate mixer tube circuits, means to supply energy output from one of the single pulse relays and also energy at the frequency F/M to

one of the mixer circuits, means to supply energy output from the other single pulse relay combined with frequencies at frequencies F and F/M and the output of the square wave generator to control the other of said mixer tube circuits, and a common load circuit to combine the outputs of the said mixer circuits.

7. In synchronizing apparatus for synchronizing interlaced television systems, a source of oscillatory energy of a frequency F , where F represents the picture line frequency multiplied by the number of picture fields per picture frame, means to derive from the source of oscillatory energy other energy at frequencies F/N , F/M and F/AM , where N represents the number of picture lines per picture frame, M represents the number of picture fields per picture frame and A represents a whole number greater than unity, an output circuit, means to supply energy at a frequency FM to the output circuit, means to supply energy at the frequency F to the output circuit, means to serrate the energy developed at a frequency F/M , means to supply the serrated energy to the output circuit, and means to interrupt the transfer of the energy at frequencies F/M and F/N under the joint control of energy developed at frequencies F/M and F/AM .

8. Synchronizing apparatus for developing synchronizing signals for controlling interlaced television systems comprising a source of oscillatory energy for generating steep front asymmetric impulses at a frequency F , where F represents the picture line frequency multiplied by the number of picture fields per picture frame, a frequency divider means to derive from the source of oscillatory energy other energy at frequencies F/N , F/M and F/AM , where N represents the number of picture lines per picture frame, M represents the number of picture fields per picture frame and A represents a whole number greater than unity, an output circuit, means to supply energy at a frequency F/M to the output circuit, means to interruptedly supply energy at the frequency F to the output circuit, means to serrate the energy developed at a frequency F/M , means to supply the serrated energy to the output circuit, and means to interrupt the transfer of the energy at frequencies F/M and F/N under the joint control of energy developed at frequencies F/M and F/AM .

KURT SCHLESINGER.
